BED STAY

Application filed February 20, 1929. Serial No. 341,409.

This invention relates to a furniture stay or joint tightening devices for beds and other pieces of furniture having the usual supporting legs, side rails and end rails.

It is well-known that in this class of furniture the joints between the legs and side rails and also between the legs and end rails are subjected to more or less severe strains according to the load carried thereby and also when moving the bed from place to place with more or less load thereon resulting in frequent loosening of said joints and consequent weakening of the entire frame which renders the furniture unsafe and liable to breakage or serious impairment at any time.

The main object of the present invention is to provide a simple and comparatively inexpensive bed stay which may be more easily and quickly adjusted and which is more efficient in its operation than has heretofore been practised.

One of the specific objects is to enable all four joints between the posts and rails to be uniformly tightened by a single operation.

Another object is to enable the joints between each pair of end posts and the rails to be simultaneously and uniformly tightened by means of a single wire through the medium of a saddle piece over which the wire is adapted to render during the tightening operation.

A further object is to provide each wire with a pair of loops, each adapted to receive one of the end legs near the rails and around

which the loops are adapted to render as they are tightened by the drawing together of the saddles, one for each pair of end legs.

Another object is to arrange the saddles in the longitudinal center of the bed frame and between the end rails thereof so that when the wire loops are engaged with the posts the drawing of the saddles toward each other will cause a corresponding tightening of the wire loops toward the center of the bed frame to effect the simultaneous tightening of the legs against the adjacent ends of the side rails as well as against the adjacent ends of the end rails.

50 Other objects and uses relating to specific

parts of the bed stay will be brought out in the following description.

In the drawings:

Figure 1 is an inverted plan of a portion of a bed frame including the corner posts, side rails and end rails together with my improved joint tightening device in operative engagement with the posts near their junctions with the rails. 55

Figure 2 is an enlarged longitudinal sectional view, partly broken away, taken in the plane of line 2—2, Figure 1, the outer ends of the wire loops being broken away. 60

Figure 3 is an enlarged transverse vertical sectional view taken in the plane of line 3—3, Figure 1, showing two of the wire loops of one of the tightening wires, partly broken away, but in operative engagement with one of the saddles. 65

Figure 4 is a perspective view on a reduced scale of one corner of the bed frame, showing one of the wire loops in operative position with one of the corner posts directly below the rails. 70

Figure 5 is a face view of a modified form of wire-tightening device. 75

The tightening device may be used in connection with any furniture frame having the usual corner legs —a—, side rails —b— and the end rails —c— in which the side and end rails are detachably or otherwise joined to the posts by conventional couplings commonly used in beds, and analogous pieces of furniture. 80

As illustrated, the tightening device or bed stay comprises a rod —1— upon which is mounted a pair of similar but reversely arranged saddles —2— for relative lengthwise movement thereon together with separate pairs of wire loops —3—, one pair for each of the saddles —2— and each pair adapted to impress two of the corner posts —a—, as shown in Figure 1. 85

The loops —3— of each pair are preferably made of a single piece of wire having its opposite ends connected by links —4— to opposite ends of the corresponding saddle —2— and its central portion slidably engaged with the corresponding saddle while the loops —3— for each saddle receive and 90

embrace the corresponding pair of end legs —a—.

The saddles —2— are preferably crescent-shaped in plan and arranged with their con-

5 vex sides facing each other or the concave sides facing the ends of the bed when the tightening device is adjusted for use.

The saddles —2— are provided with apertures —5— therethrough midway between 10 their ends and in axial alinement with each other for receiving the supporting rod —1—, as shown more clearly in Figure 2.

The inner convex sides of the saddles are provided with parallel longitudinal grooves 15 —6— in places above and below the central openings —5— and —5'— for receiving the intermediate portions of the wires forming the separate pairs of loops —3— and holding said wires against vertical displacement from 20 the saddles but at the same time permitting the adjacent portions of the wires to slide endwise on the saddles to compensate for varying tensions on the opposite sides of each loop.

25 One of the apertures as —5— in the corresponding saddle —2— is of smooth bore to permit said saddle to slide endwise thereon or rather to permit the rod —1— to slide endwise therethrough when assembling the various parts of the tightening device.

30 The aperture 5' in the other saddle is preferably threaded to engage the adjacent threaded end 1' of the rod 1. The other end of the rod 1 extends through and some distance beyond the saddle 2 having the smooth bore 5 and terminates in a handle 7 by which it may be turned.

35 A collar 8 is adjustable lengthwise of and upon the rod —1— to compensate for beds 40 of different sizes and is held in its adjusted position by a set screw 9 engaging one or the other of a series of notches 9' in the periphery of the rod as shown in Fig. 2. This collar 8 engages the outer face of the adjacent 45 saddle 2 when the rod 1 is rotated by hand to tighten the loops 3 upon their respective posts a. In the wire-tightening device shown in Figure 5 both of the saddles are provided with threaded central apertures, one being 50 a right hand thread and the other a left hand thread for receiving and engaging correspondingly threaded end of a connecting rod 20 having its intermediate portion provided with a handle 21 by which it may be turned 55 in opposite directions to move the saddles toward and from each other.

Operation

60 The wire loops of each pair may be pre- attached to their respective saddles before applying the same to the posts —a— in which case the loops could be placed from the underside of the legs upwardly around the same into close proximity to the underside of the 65 adjacent portions of the rails —b— and

—c— after which both saddles will be drawn toward each other by the tightening of the screw rod —1— to place the loops under the desired tension.

Or, the central portions of the wire form- 70

ing each pair of loops might be engaged in one of the grooves —6— of the corresponding saddle —2— and the ends of the wire would be drawn around two of the corresponding posts close to the adjacent portions 75 of the rails —b— and —c— and returned to the corresponding ends of the saddle and attached thereto by the coupling members —4—, it being understood that the ends of each saddle are provided with apertures 80 —10— for receiving the adjacent coupling members as shown more clearly in Figures 2 and 3.

The saddles —2— are relatively short as compared with the width of the bed frame 85 while the rod —1— is relatively short as compared with the length of the frame so that when the tightening device is placed in operative position for stiffening the frame 90 of a bed or analogous piece of furniture the rod —1— will extend along the longitudinal center and substantially midway between the ends of the bed frame and, therefore, the saddles —2— will be located substantially midway between the sides and ends of the frame. 95

It, therefore, follows that when the loops 100 —3— are engaged with the legs of the frame those of each pair will converge inwardly to the ends of the corresponding saddle so that when tightened by a proper adjustment of the screw rod —1— the resultant pull of the loops upon the posts will be toward the center of the frame thereby drawing each leg 105 against the adjacent ends of the rails —b— and —c— in one operation.

That is, the effect of tensioning the loops 110 —3— will be to draw the legs toward the center of the frame and thereby to stiffen all four joints between the legs and rails in one and the same tightening operation.

115 It will be noted that during this tensioning of the loops —3— the loops are free to slide around their corresponding legs to compensate for unequal tension on opposite sides thereof and at the same time the intermediate portions of each wire from which the loops of each pair are formed is free to slide upon its corresponding saddle —2— to additionally compensate for varying tensions upon opposite sides of each loop.

120 What I claim is:

1. The combination with a piece of furniture having four legs, of a stay comprising 125 a pair of saddles, means for adjusting the saddles toward each other and for holding them in their adjusted positions, and a pair of stay-wires one for each saddle, each stay wire being continuous from end to end and having its ends attached to opposite ends of its corresponding saddle and its central portion 130

slidably engaged with its saddle and its remaining portion bent into loops diverging from the opposite ends of the adjacent saddle and embracing two of the legs to exert inward stress upon said legs along the inwardly converging lines of the loops when tightened, said loops being free to open and close to conform to legs of different sizes.

- 5 2. In a device for tightening the joints between the legs and frame of a piece of furniture, a crescent shaped saddle having its concave side and points facing two of the legs, and a one-piece wire having its ends attached to said points and its central portion 10 slidable lengthwise of and upon the convex side of the saddle and its remaining portions constituting loops divergent from the ends of the saddle for receiving said legs, and means for adjusting the saddle in the direction of convergence of the loops.
- 15 20 In witness whereof I have hereunto set my hand this 4th day of February, 1929.

JOHN HENRY DE BOER.
